UNITED STATES PATENT OFFICE.

CHESTER McNEIL, OF CHICAGO, ILLINOIS, ASSIGNOR TO THE UNION SPECIAL SEWING MACHINE COMPANY, OF CHICAGO, ILLINOIS, A CORPORATION OF ILLINOIS.

COVERED SEAM FOR SEWED ARTICLES.

SPECIFICATION forming part of Letters Patent No. 703,966, dated July 1, 1902.

Application filed April 26, 1899. Serial No. 714,579. (No model.)

To all whom it may concern:

Be it known that I, CHESTER McNEIL, a citizen of the United States, residing at Chicago, in the county of Cook, State of Illinois, have 5 invented certain new and useful Improvements in Covered Seams for Sewed Articles, of which the following is a description, reference being had to the accompanying drawings, and to the letters and figures of reference marked thereon.

My invention relates to an improvement in seams for sewed articles; and the object especially is to provide a covered seam in which two pieces of fabric are superposed and united 15 by a row of stitching along the edge and then spread out flat, the raw edges being covered by other threads.

The invention consists of a new combination of fabric and threads whereby this covered seam is produced, this combination consisting of two pieces of fabric whose edges have been superposed and united by a row of straight stitches along the edges and then spread out flat and parallel rows of loops 25 passed through the fabric on opposite sides of the line of the seam entering and emerging on the same side of the fabric and cross-threads concatenating with said rows of loops.

Furthermore, the invention consists in the 30 matters hereinafter described, and referred to in the appended claims.

The invention is illustrated in the accompanying drawings, in which—

Figure 1 is a plan view showing a seam for 35 sewed articles constructed in accordance with my invention. Figs. 2 and 2^a are side views of the stitch, the former showing a seam where the upper or needle threads are passing entirely through the fabric, while in the 40 latter the material is of such thickness that the threads simply take into it. Fig. 3 is a plan view of the fabric upon the opposite side from that shown in Fig. 1.

In the drawings, A represents two pieces 45 of fabric whose edges have been first superposed and then united by a straight line of stitching a and then spread out flat, the raw edges thereof being marked b.

B represents rows of loops passed through 50 the fabrics upon opposite sides of the middle

line of the seam, each loop entering on one side of the fabric and emerging on the same side ahead of its point of entrance.

For example, as shown more particularly in Figs. 2 and 2^a, 1 represents the starting-point, the needle passing through the fabric and emerging at the point 2, forming the loop B. A cross-thread, the starting-point of which is illustrated at 3, is then passed through the needle-loops. Then the needles back out 60 of the material when the machine feeds, the looping device retaining the needle-loops around it, when the needles again enter the material, coming out at 4 and passing between the looper and its thread when the looper 65 backs out of the needle-loops of the previous stitch, thus leaving its own thread around the needles, the result of which is that the looper-thread is left around the needle-thread in the stitch succeeding that in which it was 70 first carried through the needle-loops. These cross-threads form the large loops c, and thus the stitch may be briefly described as consisting of the rows of loops B passed through the fabric, the threads thereof entering and 75 emerging from the same side and the cross-threads passing through the loops B and diagonally across the line of the seam around the second pair of loops B, back through the first set of loops B, then through the second 80 set of loops B, and so on, giving to the stitch the appearance shown particularly in Fig. 1 of the drawings and covering the raw edges of the fabric.

In Figs. 2 and 2^a a seam is shown, in the 85 former the upper or needle threads being represented as passing entirely through the fabric, while in the latter the material is of such thickness that the threads simply take into it.

It will be understood that in the formation 90 of this seam the body of the goods is crimped over a substantially V-shaped piece on the throat-plate of a sewing-machine, a presser-foot correspondingly grooved on its under side coöperating therewith, the needles passing through the goods entering and emerging on the same face of the fabric, this being a common way of holding goods on blind-stitch machines, as illustrated, for example, in machine shown in application for Letters Patent 100

filed March 29, 1899, Serial No. 711,025, and known as the "Union Special Blind-Stitch Machine."

Having thus described my invention, what I claim as new, and desire to secure by Letters Patent, is—

1. A seam for sewed articles, including a fabric, and parallel rows of loops passed into the fabric and out again upon the same face of the fabric in advance of the entering point, whereby the loops lie in the direction of the length of the seam, and an interlocking cross-thread for locking the loops upon the upper surface of the fabric at the point where they emerge therefrom; substantially as described.

2. The herein-described covered seam for sewed articles, comprising the two pieces of

fabric A arranged with their edges abutting and united by a line of stitching α and a row of loops passing into each fabric and out again upon the same face of the fabric in advance of the entering point, said rows being parallel with each other, whereby the loops lie in the direction of the length of the seam, and an interlocking cross-thread for locking the loops upon the upper surface of the fabric at the point where they emerge therefrom, substantially as described. 20 25

In testimony whereof I affix my signature in presence of two witnesses.

CHESTER MCNEIL.
